(57) **CLAIM**

The ornamental design for a garden edging, as shown and described.

DESCRIPTION

FIG. 1 is a perspective view of the garden edging showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side thereof; and,

FIG. 7 is a right side view thereof.

The broken lines in the drawings represent portions of the garden edging and form no part of the claimed design.

The garden edging is shown with a symbolic break in its length and height. The appearance of any portion of the garden edging between the break lines forms no part of the claimed design.
